SHEARMAN BOTTESE, OF WASHINGTON, DISTRICT OF COLUMBIA.

TRUCK.

1,122,849.

Specification of Letters Patent.

Patented Dec. 29, 1914.

Application filed March 14, 1914. Serial No. 824,662.

To all whom it may concern:

Be it known that I, SHEARMAN BOTTESE, a citizen of the United States, and a resident of Washington, in the District of Columbia, have invented an Improvement in Trucks, of which the following is a specification.

The present invention relates to improvements in the corner posts and correlative parts of vehicle bodies, particularly wagons and trucks.

One of the principal objects of the invention is to provide an extensible corner post having means adapted to coöperate with swinging sides and end gates comprising hinged upper and lower sections for maintaining said sides and end gates in upright or lowered position, whether one section of the sides and end gates are to be held in upright or lowered position, or both sections are to be maintained in said positions.

Another object is the provision of a device of the class described which will be simple, durable, efficient in operation and inexpensive to manufacture.

With these and other objects in view which will become apparent as the description proceeds, the invention resides in the construction, combination and arrangement of parts hereinafter more fully described and claimed, and illustrated in the accompanying drawing in which like characters of reference indicate like parts throughout the drawing, of which—

Figure 1 represents a perspective view of one corner of the vehicle constructed according to my invention, the end gate being shown in upright position with the sections extended, and the side being shown in upright position with the sections folded, Fig. 2 represents a vertical sectional view taken longitudinally of the vehicle or at right angles to the end gate, through the corner post, the end gate being shown partially in section, Fig. 3 represents a horizontal sectional view taken on the plane indicated by the line 3—3 of Fig. 2, Fig. 4 represents a horizontal sectional view taken on the plane indicated by the line 4—4 of Fig. 1, the end gate being shown in lowered position, and the side being shown in lowered position and lying upon the vehicle floor, Fig. 5 represents a top end view of a modified form of extension rod, and Fig. 6 represents

a side elevational view of the upper end 55 thereof.

Referring more particularly to the drawing, the numeral 5 indicates one corner of a vehicle floor, which may be mounted upon suitable running gear (not shown). At each corner of floor 5 is secured a hollow post 6, in the form of a cylinder having a circular base flange 7 formed at its lower end which rests upon floor 5, and is secured thereto by means of a plurality of bolts 8 extending through said base flange and through the floor. The hollow post registers with the opening 9 extending through the floor.

Slidably positioned in the post 6, is an extension rod 10 which is preferably solid, 70 and which is of a diameter less than the inside diameter of the post, and is slidably positioned in a filler or cylindrical bearing 11, secured in any suitable manner in the upper end of post 6, said extension rod having a 75 sleeve 12 surrounding it at its lower end, said sleeve being of a diameter substantially equal to the inner diameter of the post, whereby when said extension rod is raised, sleeve 12 will snugly fit within post 6 to co- 80 operate with bearing 11 in maintaining the rod in rigid position, said rod when in lowered position, as shown in Fig. 2, extending through the opening 9 in floor 5 somewhat below said floor.

The sides A and end gates B comprise upper and lower hinged sections 13, 14, 15 and 16 respectively, and the sides are disposed near the lateral edges of the floor between the corner posts, while the end gates are disposed adjacent the transverse end edges of the floor between the corner posts.

Secured to the base flange 7 of each corner post, is a bearing frame 17, which is substantially arcuate in form, and conforming to the curve of the post and comprising a section of stout wire or rod bent into the required form and suitably secured to the base plate in spaced relation to the post. The lower sections 14 and 16 respectively of the sides and end gates are provided at their lower edges with pintle pins 18, which at their outer ends are turned upwardly to form hooks, and extend into engagement with the bearing frames between the uprights 19 of said frames, and the adjacent posts, in such a manner that the sides and end gates will be held against

lateral movement whether they be in upright or lowered position. The pintle pins are so formed that the sides and end gates may be removed at will from their position on the floor.

In Fig. 1 the end gate B is shown as in upright position with the section 15 extended, while the side A as is shown in upright position with its section 13 in folded position, and the rod 10 is shown as extended, in order that latching means carried thereby for the purpose, may be brought into position whereby to hold the end gate in upright position. This latching means 15 comprises a substantially L-shaped clip 20 bent at its central portion over a sleeve 21 rigidly secured on the upper end of rod 10, and held in engagement with said sleeve by means of a wire fastening 22 spanning said 20 clip and bent at its ends around the rod 10 below and above the sleeve 21, a cotter pin 42 being extended through rod 10 above the wire 22 for preventing the displacement of said clip and securing means from said rod. 25 The ends of clip 20 lie at substantially right angles with each other and in the general directions of the sides and end gates, and pivotally secured to the other faces of the 30 ends of said clip are a pair of latches 23 provided with hook portions 24 at their ends, adapted to engage in openings in the upper edges of the sections of the sides and end gates.

As shown in Fig. 1, the end gate has its 35 sections extended in upright position, side A is in upright position with its upper sections 13 folded downwardly over section 14, and in order to secure section 14 in upright position, or section 16 of the end gate, should said gate and side be in opposite 40 relative positions, there is swiveled on rod 10 by means of an eye 25 formed at its inner end, a latch 26 similar to latches 23 and adapted to engage in openings in the upper 45 edges of sections 14 or 16, as the case may be. When the end gates and sides are all in upright position and the sections folded one upon the other, the extension rods will be lowered so that the latches 23 may engage 50 the openings in the upper edges of the lower sections of said end gates and sides for holding them in upright position.

The end gate B in Fig. 2, is shown as having its sections in folded position, and 55 as being in partially lowered position, and in order to hold said gate in the position shown, or in totally lowered position, a chain 27 is provided, connected at one end to a hook 28 engaging over rod 10 above post 6, said chain being passed through openings 29, surrounded by metal eyes 30 and positioned adjacent the ends of section 16 of the end gate, and between the cross-bars of the section 15 of said gate, and engaged at its opposite end with hook 28 by

means of a second hook 31 carried by said chain. When the end gates or sides are in the position occupied by the end gate in Fig. 1, the chains may hang loosely within or without the vehicle body, or may be otherwise disposed as to most conveniently suit the requirements. It is obvious since each of the corner posts is provided with one of the chains, that either one of the end gates or sides may be lowered and held in any 70 lowered position by means of the chains.

The sections of the sides and end gates are provided with hinges that may be disconnected from each other so that the upper sections of the sides or end gates may be removed at will, said hinges including pintle pins 32 secured to the lower sections and hinge leaves 33 in the form of hooks secured to the lower edges of the upper sections and adapted to engage said pintle pins.

In the modified forms shown in Figs. 5 and 6, the upper end of rod 10 is reduced as at 34, and on the reduced portion is swiveled a clip 35 having arms 36 extending therefrom at right angles to each other, said clip 90 being preferably formed of a solid piece of material, and the upper end of the reduced portion 34 is threaded to receive a nut 37 by means of which the clip 35 may be retained in place. Pivoted to arms 36 on their outer faces, are a pair of latches 38 each formed of a suitable flat piece of material, and provided at their outer ends with curved hooks 39 off-set from the latches toward the inner faces thereof, and said hooks are 100 adapted, when in use, to engage in recesses 40 formed within the inner overhanging edges of the binding strips 41 provided on the upper edges of the sections of the sides and end gates of the vehicle. It is my intention to use the modified form of clips and 105 latches on vehicles of heavy construction, but it will be understood that they may be readily used on vehicles of ordinary construction, it being at the option of the builder which form he will use.

Although I have described the preferred embodiment of my invention, I may desire to make such changes in the construction, combination and arrangement of parts 115 thereof, as do not depart from the spirit of the invention or scope of the appended claims.

I claim:

1. A device of the class described, comprising a vehicle floor, a hollow post secured near each corner thereof, a bearing sleeve in the upper end of each post, an extension rod slidable in said sleeve and extending within said post, and normally 120 through an opening in said floor with which said post is in registration, a sleeve carried by the lower end of said rod and adapted to engage within said post when said rod is extended, a sleeve secured on said rod above 125

the post, a clip comprising a strip of material bent at right angles around last said sleeve, a wire spanning said strip and engaging said rod on each side of last said 5 sleeve for retaining the clip in position, a skeleton bearing frame positioned in spaced relation to each of said posts at its bottom portion, sides and end gates positioned on said floor between said posts and having 10 pintle pins adapted to engage said bearing frames, said sides and end gates comprising sections removably hinged together, latches pivoted to said clip and adapted to engage in openings in the upper edges of said sections 15 for holding the same in upright position, a latch swiveled on said extension rod and adapted to engage the lower section of one of the side or end gates when the adjacent side or end gate is in extended and upright 20 position, and a chain connected at one end to said rod, said chain adapted to extend through openings in the sections of the sides and end gates, for maintaining them in adjusted lowered position, said sides and 25 end gates provided with metal eyes surrounding said openings.

2. The combination with a vehicle floor having corner posts comprising upper and lower telescoping sections, of a sleeve secured to said upper section, an angular clip engaging said sleeve, a wire spanning said clip at a plurality of points and engaging the upper section above and below said sleeve, extensible sides and end gates positioned on said floor between the posts, said 30 clip having latches pivoted thereto and provided with hooks adapted to engage openings in said sides and end gates for maintaining them in upright position, a latch swiveled on said upper section and adapted to engage one of the sides or end gates when the adjacent side or end gate is in extended 35 upright position, a hook supported by said upper section, and a chain connected to said hook, said chain adapted to be passed through openings provided in said sides and end gates for maintaining them in adjusted lowered position.

3. The combination with corner posts of 40 a vehicle comprising telescoping upper and lower sections, of a clip secured to each upper section, said clip having arms extending at right angles to each other, latches pivoted to said arms and provided with 45 hooks, and extensible sides and end gates positioned between the corner posts, said latches adapted to engage said sides and end gates for holding them in upright position, and a latch swiveled on each upper section 50

below its clip, said latch comprising an arm 60 having a hook formed at its end and adapted to engage an opening in one of the sides or end gates, while the adjacent side or end gate is in extended and upright position.

4. A vehicle corner post comprising a 65 hollow cylinder having a base flange surrounding one end thereof, a vehicle floor on which said base flange is adapted to rest, bolts extending through said flange and floor for securing the post on the latter, 70 said floor provided with an opening registering with the interior of the cylinder and of a diameter equal to the inside diameter of said cylinder, a bearing sleeve secured in said cylinder, and an extension rod slidably carried by said sleeve, said rod normally extending through said opening and depending below said floor, said rod provided at its lower end with a sleeve adapted to snugly fit within said cylinder when the 75 extension rod is in extended position.

5. In a vehicle, the combination with extensible corner posts secured to the floor thereof and comprising upper and lower telescoping sections, of sides and end gates, 80 means for removably pivoting said sides and end gates on said floor, said sides and gates comprising upper and lower hinged sections, binding strips secured to the edges of said sections and extending inwardly 85 therefrom, a clip secured on the upper section of each corner post and including arms extending at right angles to each other, hooks pivoted to said arms, and adapted to engage in openings in said binding strips 90 for securing the sides and gates in upright position, a hook swiveled on each upper section of the posts and adapted to engage the lower section of one of the sides or end gates for retaining the same in upright position 95 when the adjacent side or end gate is in upright extended position.

6. The combination with a corner post comprising telescoping sections, of a clip secured to one of said sections, said clip including arms extending at right angles to each other, and hooks pivoted to said arms, and means for securing said clips, said means including a sleeve on one of said sections against which said clip engages, 100 and a wire spanning said clip and engaged around its adjacent section on opposite sides of the sleeve.
